UNITED STATES PATENT OFFICE

WILLIAM E. WINE, OF TOLEDO, OHIO

CAR-DOOR DEVICE

Application filed November 16, 1923. Serial No. 675,099.

This invention relates to railway cars and more particularly to an improved hopper construction and door arrangement therefor, together with improved means for holding the doors firmly to their seats and substantially sealing them.

An important object of my invention, generally stated, is to provide supporting means which will serve as an emergency stop for preventing unlatching of the doors in case they become distorted or loose, the supporting means also acting to insure proper closing of the door against its seat.

Another object is the provision of fulcrum means whereby a pinch bar or its equivalent may be engaged with the door arm and with the supporting member whereby to permit forcing of the door to its closed position practically regardless of the extent to which it may be distorted.

Another object is the provision of a peculiar bracket member which serves as the support for the door securing hook and which has formed integral therewith the extension support which constitutes the emergency stop and the fulcrum for the door closing pry bar, the bracket and hook structure being capable of manufacture as a unit adapted to be engaged upon an existing hopper for effecting securing of the door thereof.

The invention further contemplates the improvement of door spreaders or stiffeners and door arms whereby their efficiency will be increased, together with minor improvements in the general structural assembly.

To the attainment of the foregoing objects and advantages, the invention consists in the details of construction and arrangement of parts to be hereinafter described and pointed out in the appended claims, although it should be understood that the present forms are merely exemplifications of preferred structure and that various changes and modifications may be made without departing from the salient features of the invention as pointed out in the appended claims.

In the drawings chosen to illustrate two possible embodiments of the invention:

Figure 1 is a partial side elevation of a car hopper modified and equipped in accord-

ance with the principles of the present invention.

Figure 2 is a transverse section on the line 2—2 of Figure 1, portions of the structure being omitted.

Figure 3 is an elevational view of a portion of a door and the associated locking members.

Figure 4 is a plan view of the end of the door spreader and door arm.

Figure 5 is a view in plan of one of the doors, drawn to a smaller scale.

Figure 6 is an end elevation of the door with the hinge and stiffener omitted.

Figure 7 is a view similar to Figure 1, showing, however, a slightly modified arrangement of stiffening member, door arm and sealing flange.

Figure 8 is a transverse section on the line 8—8 of Figure 7, portions of the structure being omitted.

Figure 9 is a view similar to Figure 3 showing the modified construction illustrated in Figures 7 and 8.

Figure 10 is a detail section on the line 10—10 of Figure 8.

In the drawings wherein similar reference characters designate corresponding parts throughout the several views, I have shown a portion of a hopper of the type used in twin hopper cars, it being unnecessary to illustrate more than this inasmuch as the construction of cars of this type is so well known. The hopper includes a side sheet 1 and the sloping or floor sheet 2 equipped at its transversely extending edge with a stiffening angle bar 3 secured thereto, as for instance, by rivets 4. The edges of the side sheets 1 and floor sheet 2 define the discharge opening for the lading and this opening is ordinarily closed by a door 5 which is preferably of plate-like construction and formed with peripheral flanges 6 which operate to reinforce and stiffen the same. The door is of such size that it projects outwardly beyond the edges of the side sheet 1 and floor sheet 2. The peripheral flanges referred to cooperate with certain elements of the invention to be hereinafter described so as to have a sealing effect.

Doors of this type are ordinarily hinged

to the car body above the hopper discharge opening with the axis of the hinge pintles extending transversely of the car. In this present instance the numeral 7 designates hinge leaves carried by the door and terminating in knuckles 8 which cooperate with and which are pivoted to the hinge pintle carried by or fastened to the car in the ordinary manner. There are usually two hoppers per discharge openings at an end of a car of the type indicated and the doors for closing the same are mounted in pairs alining with each other and connected by means of a spreader 9 which may be secured by rivets 10 or the like. The spreader is usually fastened to both doors so that they may be operated in unison and thereby form in effect a single door which may be said to consist of spaced sections. As this construction is well known in the art it is not shown in complete detail on the drawings. The spreader is conveniently formed as a channel bar having its web lying flat against and secured to the outer side of the door by the securing elements 10 referred to, the flanges of the channel extending outwardly away from the door. This type of spreader is easily manufactured and in many instances is better adapted to meet existing conditions than a spreader of some other cross sectional configuration. Secured to the outer end of the spreader and to the door, as by means of rivets 11 and 12, respectively, is a door arm 13 which may be of angle bar construction and which has one end portion offset at 14 for the accommodation of the hinge leaf 7 and its other end angularly deflected or offset to pass by the flange 6 at the end of the door.

An important feature of my invention is the provision of an angular strip or bar 15 located at the edge of the side sheet 1, said bar being provided with a flanged portion 16 lying against and secured to the outer side of the said side sheet, as for example by rivets 16a. This bar further includes an outstanding portion 17 which extends outwardly from the hopper at the edge of the discharge opening and which serves as an abutment for the door when the latter is closed. This portion 17 of the strip merges into a flange 18 which may be substantially parallel with the door flange 6 and located outwardly thereof to act as a seal when the door is closed. By referring to Figure 2 it will be noted that when the plane of the side plate 1 does not extend at right angles to the plane of the door, the flange 18 of the strip or bar 15 may be inclined with respect to the side sheet 1 to correspond to the direction of the door flange 6. At this point it should also be stated that if preferred, the door may be formed with corrugations or pressed out ribs 19 which lie approximately parallel with the marginal flanges and which not only serve to stiffen the door but also to co-act with the

hopper at the edges of the side sheets thereof to form an additional seal for the lading of the car.

For holding such doors closed I provide a substantially self-contained securing mechanism which includes a cast bracket 20 mounted upon the side sheet of the hopper in such position as to overlie the angular strip or bar 15 thereon. This bracket preferably includes a main or plate portion 21 having spools or lugs 22 thereon seating against the side sheet 1, said spools serving to space the bracket away from the side sheet in substantially parallel relation with the flange 18 of the strip or bar 15. A cover plate 23 is provided to overlie the pivoted end of the securing hook 24 which is of that type having successive ledges 25 and 26 adapted to engage the door arm 13 for holding the door in nearly or entirely closed position. I have illustrated rivets 27, 28 and 29 which serve to hold this bracket and cover structure upon the hopper. The rivet 28 additionally acts as the pivot for the hook 24 and the rivet 29 serves as the pivot for a locking cam 30 which is provided for the purpose of holding the hook 24 in engagement with the door arm 13 so that accidental displacement will not occur.

On account of the severity of the service, doors of this general character sometimes loosen and sag down away from their hinge pintles and as a consequence, the doors may become unlatched or the door arms thereof become so positioned as to prevent the doors from being properly latched. In order to prevent these defects, the bracket 20 is provided with an extension 31 preferably integral therewith, said extension projecting outwardly beyond the edge of the hopper side sheet and beyond the plane of the closed door. This extension extends beneath the free end of the door arm 13 and its edge 32 is inclined so as to intersect the arc of swing of the door arm thereby forming an approach plane for the said arm. By this construction it will be seen that when the door has sagged from loosening or distortion of the parts from wear or other causes, the extension 31 constitutes an auxiliary stop for arresting movement of the door downwardly and away from its hinge pintles. Furthermore if the door has sagged on account of the conditions mentioned, the edge 32 of the extension is so formed and arranged with respect to the door arm and door hook, that the door may be readily swung to a position of preliminary closure, but upon moving the door to a more fully closed position, the door arm will engage and move along said edge thereby forcing the door upwardly toward its hinge pintles into normal fully closed position.

It will be observed that reference has been made to preliminary closing position and

fully closed position, depending upon whether the ledge 25 or 26 be engaged with the door arm. In explanation, it should be stated that the door may be easily swung manually into such position that the ledge 25 will engage the arm 13. For moving the door so that the arm will be engaged by the ledge 26, with the door seating against the abutment flange 17, it sometimes becomes necessary to employ lever means such as a pinch bar, lever, long handled wrench, or the like. To permit such action, the outer end of the door arm 13 is formed with a preferably elongated opening 33 constituting a seat through which a pinch bar, illustrated at 34, may be inserted, and the outer end of the extension 31 is provided with a socket 35 constituting a fulcrum within which the lower end of the pinch bar may be seated. This socket is preferably open at the outer face of the extension and is located inwardly of the opening 33, with respect to the side of the car so that the outer or upper end of the pinch bar will extend upwardly and outwardly with respect to the car and thus be readily accessible to an operator. By applying the lever as described and as shown in Figure 3, the door may be forced from partly to fully closed position even though the parts may be badly distorted, loose from wear, or otherwise deranged. The wall 36, at the end of the socket, or at the end of the extension 31, is preferably thickened as it extends upwardly, both the inner and outer surfaces diverging and the upper edge 37 being rounded so that the pinch bar or lever may rock upon the crown of the edge. The shape of the socket is such that the inner edge may be said to overhang the bottom of the socket to a limited extent for preventing the pinch bar from slipping out when fulcrumed in the socket during the operation of forcing the door shut. This socket is most clearly illustrated in Figure 10 which is common to both embodiments of the invention. It will of course be appreciated that in addition to employing the prying or fulcrum means for forcing the door to fully closed position, it may be used to force the door open should it become stuck or frozen in closed position. To accomplish this result the lever is operated in a direction opposite to that when the door is being forced shut, its lower end cooperating with the wall of the socket opposite to wall 36.

In Figures 7, 8 and 9 there is illustrated a slightly modified arrangement through the general construction and most of the specific details are the same as above described. In this form, however, the angular strip or bar 15 is replaced by a stiffening bar 38 which may be riveted or otherwise secured to the side sheet 1, as indicated at 39. This stiffening bar forms a solid base for the bracket structure 20 above described, which bracket carries the hook 24. The bar 38 is located

at a point spaced back somewhat from the edge of the sheet so as to leave a projecting portion which is laterally deflected at an angle to provide a flange 40 against which the adjacent flange 6 of the door is intended to cooperate for insuring a substantially tight joint. The other point of difference in this variation is that the spreader 41 is formed as a Z-bar instead of the above described channel bar, one flange 42 of the Z-bar lying against and being riveted or otherwise secured to the door, as shown at 43. The web of the Z-bar is outstanding with respect to the door and its other flange 44 lies parallel with and somewhat removed from the door. The door arm 45 is in this instance secured to the sheet 1, as for example by rivets 46, and may also be secured to the Z-bar spreader, as indicated at 47. The door arm lies above the Z-bar and its free end portion 48 is offset so as to clear the flange 6 on the door. In other respects this form of the invention is the same as the first described form and its operation is identically the same.

I claim:

1. A railway car having a hinged door for closing a discharging opening of a hopper thereof, a pivoted member adapted to releasably maintain said door in closed position, a bracket affixed to the car body and embodying a supporting base for the pivoted member, said bracket having an extension arranged to project beyond the plane of the door when the latter is in closed position constituting means for arresting movement of the door away from its hinge pintles.

2. A railway car having a hinged door for closing a discharging opening of a hopper thereof, a pivoted member adapted to releasably maintain said door in closed position, a bracket affixed to the car body and embodying a supporting base for the pivoted member, said bracket having an extension arranged to project beyond the plane of the door when the latter is in closed position, the door carrying an arm for engagement by said pivoted member, said extension having its top surface arranged at an inclination with respect to the arc of swing of said arm.

3. A railway car having a hinged door for closing a discharging opening of a hopper thereof, a pivoted member adapted to releasably maintain said door in closed position, a bracket affixed to the car body and embodying a supporting base for the pivoted member, said bracket having an extension arranged to project beyond the plane of the door when the latter is in closed position, the door carrying an arm for engagement by the pivoted member, and said extension having an inclined surface projecting beneath said arm and engageable thereby to serve as an auxiliary stop.

4. A railway car having a hinged door

for closing a discharging opening of a hopper thereof, a pivoted member adapted to releasably maintain said door in closed position, a bracket affixed to the car body and embodying a supporting base for the pivoted member, said bracket having an extension arranged to project beyond the plane of the door when the latter is in closed position, the door being provided with an arm, and said extension having a portion underlying said arm and engageable thereby for directing the door to its seat.

5. A railway car having a hinged door for closing a discharging opening of a hopper thereof, a pivoted member adapted to releasably maintain said door in closed position, a bracket affixed to the car body and embodying a supporting base for the pivoted member, said bracket having an extension arranged to project beyond the plane of the door when the latter is in closed position, said extension having a socket for the accommodation of removable door prying means.

27. 6. In a railway car having a hopper provided at its discharge end with a hinged door normally closing the same, a bracket secured to the hopper side, an arm on the door, a pivoted latch member on said bracket adapted to engage said arm for holding the door closed, said bracket having an integral extension formed with a socket for the accommodation of removable door prying means.

35. 7. In a railway car having a hopper provided at its discharge end with a hinged door normally closing the same, a bracket secured to the hopper side, an arm on the door, a pivoted latch member on said bracket adapted to engage said arm for holding the door closed, said bracket having an integral extension formed with a socket for the accommodation of removable door prying means, and the arm having an opening for the passage of the door prying means, the socket serving as a fulcrum.

8. In a railway car having a hopper provided at its discharge end with a hinged door normally closing the same, a bracket secured to the hopper side, an arm on the door, a pivoted latch member on said bracket adapted to engage said arm for holding the door closed, said bracket having an integral extension formed with a socket for the accommodation of removable door prying means, the arm having an opening for the passage of the door prying means, the socket serving as a fulcrum and having a rounded upper edge engageable by the pry means.

60. 9. In a railway car having a hopper provided at its discharge end with a hinged door normally closing the same, a bracket secured to the hopper side, an arm on the door, a pivoted latch member on said bracket adapted to engage said arm for holding the

door closed, said bracket having an integral extension formed with a socket for the accommodation of removable door prying means, the arm having an opening for the passage of the door prying means, the socket serving 70 as a fulcrum and having a rounded upper edge engageable by the pry means, said edge overlying the bottom portion of the socket for retaining the lower end of the pry means.

10. In a railway car having a hinged door normally closing a discharging opening of the hopper thereof, an arm carried by the door, a pivoted latch for engaging said arm to hold the door closed, a bracket secured to the car body and including a base for said pivoted latch and further including an integral extension arranged to project beyond the plane of the door when the latter is in closed position, said extension constituting a combined auxiliary stop for the door and a guide for 85 conducting the same to its seat and being formed with a fulcrum for the accommodation of removable door prying means.

11. In a railway car having a hopper equipped with a hinged closure door, a pivoted hook adapted to engage an arm on the door for holding the door in closed position, a bracket secured to the hopper adjacent an edge of the door and providing a pivotal support for the hook, said bracket being 90 formed with a rigid extension projecting beyond the plane of the closed door and beneath the door arm, one edge of said extension being inclined so as to intersect the arc of swing of the door arm.

12. In a railway car having a hopper provided with a discharging opening, a door hinged to the hopper for closing said opening, a bracket secured to the hopper adjacent the discharging opening, a hook pivotally mounted 105 on the bracket and adapted to cooperate with a door arm on the door for holding the door in closed position, said bracket being formed with a rigid extension projecting beyond the plane of the closed door and beneath the door arm, one edge of the said extension constituting, in the event of sagging of the door, an approach plane for the door arm.

13. A railway car having a hopper provided with a lading discharging opening, a door for closing said opening and provided with a door arm extending laterally therefrom, a hook associated with the door arm for securing the door in closed position, and a bracket carried by the hopper adjacent the opening thereof and constituting a pivotal support for the hook, said bracket having an integral extension projecting beyond the plane of the closed door and beneath the door arm, and being provided at its outer end with a seat for a removable door prying lever.

14. In a hopper car construction, a casting adapted to be secured to the car body adjacent an edge of the discharging opening of a hopper thereof, the hopper being equipped 135

- with a door for closing the discharge opening, the casting having a portion arranged to extend beyond the plane of the closed door and equipped with an open sided socket 5 adapted to accommodate a removable door prying lever.
15. In a car having a hopper provided with a discharge opening normally closed by a hinged door, a casting adapted to be secured 10 to the hopper body, latch means on the casting engageable with an arm on the door for holding the door closed, the door arm having an opening and the casting having a fulcrum socket adapted to receive a door prying lever.
- 15 16. In a car having a hopper formed with a discharge opening normally closed by a hinged door carrying an arm, securing means for the door comprising a bracket member adapted to be secured upon the side of the 20 hopper near the opening and including separable sections, a door arm engaging hook pivoted to and between the sections of the bracket, the bracket being formed with an extension underlying the door arm and formed 25 with an open sided socket serving as a fulcrum for a door prying lever, the door arm having an opening for the passage of such lever.
- 25 17. In a car having a hopper formed with a discharge opening normally closed by a hinged door carrying an arm, securing means for the door comprising a bracket member adapted to be secured upon the side of the hopper near the opening and including separable sections, a door arm engaging hook pivoted to and between the sections of the bracket, the bracket being formed with an extension underlying the door arm and formed 35 with an open sided socket serving as a fulcrum for a door prying lever, the door arm having an opening for the passage of such lever, said opening being substantially in alignment with the fulcrum when the door is in substantially closed position.
- 40 18. In a railway car having a hopper provided with a discharge opening normally closed by a hinged door equipped with a laterally projecting arm, a hook engageable with the arm for holding the door in closed 45 position, and combined hook carrying and door supporting and guiding means comprising a bracket adapted to be secured against a side of the hopper near the discharge opening and upon which the hook is pivoted, the bracket being formed with an integral extension constituting means adapted upon a closing movement of the door and in case of sagging thereof to force the door to normal closed 55 position.
- 60 19. In a railway car having a hopper provided with a discharge opening normally closed by a hinged door equipped with a laterally projecting arm, a hook engageable with the arm for holding the door in closed position, and combined hook carrying and door 65 supporting and guiding means comprising a bracket adapted to be secured against a side of the hopper near the discharge opening and upon which the hook is pivoted, the bracket being formed with an integral extension constituting means adapted upon a closing movement of the door and in case of sagging thereof to force the door to normal closed position.
- 70 20. A railway car having a hopper provided with a discharge opening, a door for normally closing said opening having a laterally extending arm, and a member secured to the hopper adjacent the discharge opening thereof for cooperation with the door arm, said member having a portion projecting beyond the plane of the closed door and being 75 fashioned with an open sided socket constituting a fulcrum for a removable door prying lever, the latter being adapted to cooperate with said door arm for moving the door to closed position.
- 80 21. A railway car having a hopper provided with a discharge opening, a door for normally closing said opening having a laterally extending arm, and a member secured to the hopper for cooperation with the door arm and adapted to extend beyond the plane of the closed door and beneath the arm, said member having an open sided socket formed integrally therewith affording a fulcrum for a removable door prying lever, the latter being adapted to engage the door arm for moving the door to closed position.
- 85 22. In combination with a railway car provided with a hopper having a lading discharge opening, a door for closing said opening, the door being movable to open position under the influence of gravity, means for supporting the door in closed position, and means carried by the car affording a fulcrum 90 for the removable door-prying lever, the latter when operatively associated with the fulcrum extending upwardly therefrom, said fulcrum means having a portion for supporting the lever to prevent accidental downward movement of the lower end of the latter.
- 95 23. In combination with a railway car provided with a hopper having a lading discharge opening, a door for closing said opening, the door being movable to open position under the influence of gravity, means for supporting the door in closed position, and means carried by the hopper affording a fulcrum for a removable door-prying lever, the latter when in operative association with said fulcrum extending upwardly therefrom in an 100 outwardly inclined direction, said fulcrum means having a portion for supporting the lever to prevent accidental downward movement of the lower end of the latter.
- 105 24. In combination with a railway car pro- 105

vided with a hopper having a lading discharge opening, a door for closing said opening, means for retaining the door in closed position, and a member secured to the hopper affording a fulcrum for a removable door-
5 prying lever, the latter when in operative association with said fulcrum extending upwardly therefrom, said member having a shelf for supporting the lower end of the pry lever to prevent it from moving accidentally
10 downward.

25. A railway car provided with a hopper having an inclined side sheet, said hopper being provided with a lading discharge opening, a door for closing said opening, and means for retaining said door in closed position, said means involving a fixed member secured to the door and projecting outwardly beyond an edge thereof, and a pivoted member secured to the hopper side sheet and having a portion engageable with the fixed member, the plane of operation of said portion forming an oblique angle with the hopper side sheet and with the longitudinal axis of the fixed member.
20

26. A railway car having a lading discharge opening, a hinged door for closing said opening, a pivoted member operatively interposed between the door and car body for supporting the door in closed position, and a plurality or relatively movable pry bar engaging members one of which forms a pivotal support for the said pivoted member, said relatively movable members being adapted to cooperate with a removable pry bar whereby force may be applied to the door for inducing movement of the latter.
30

27. A railway car having a lading discharge opening, a gravity actuated door for closing said opening, means for supporting the door in closed position involving a movable member and a fixed member, one of said members being carried by the car body and the other by the door, and a bracket on which the movable member is mounted, said bracket being fashioned with means affording a fulcrum for a removable lever adapted to cooperate with the fixed member to induce movement of the door.
40

50. 28. A railway car having a lading discharge opening, a door for closing said opening movable to open position under the influence of gravity, and means for supporting the door in closed position involving a pivoted member and a fixed member, one of said members being mounted on the door and the other on the car body, a bracket upon which the pivoted member is mounted, said bracket being provided with an offset portion fashioned to accommodate a removable lever for forcing the door to closed position.
55

29. A railway car having a lading discharge opening, a door for closing said opening movable to open position under the influence of gravity, a bracket secured to the
65

car body adjacent an edge of the door, and means movably mounted on the bracket engageable with the door for supporting the latter in closed position, said bracket having a portion affording a fulcrum for a removable lever adapted to cooperate with the door for inducing movement thereof.
70

30. A railway car having a lading discharge opening, a door for closing said opening movable to open position under the influence of gravity, a bracket secured to the car body adjacent an edge of the door, and means for supporting the door in closed position involving a member pivotally secured to the bracket and a member fixedly secured to the door, said bracket and said fixed member being fashioned with means for receiving a removable lever whereby the door may be forced to closed position.
75

31. A railway car having a lading discharge opening, a hinged door for closing said opening movable to open position under the influence of gravity, a pivoted member mounted upon the car body engageable with the door for supporting it in closed position, and means for cooperating with a removable lever adapted to force the door to closed position, said means involving a member carried by the door forming a seat for said lever and a member carried by the car body forming a pivoted support for the hook and affording a fulcrum for said lever, said fulcrum member being arranged with respect to said seat so as to permit the lever to operate in a plane substantially parallel to the plane of operation of the pivoted door supporting member.
80

32. A railway car having a lading discharge opening, a hinged door for closing said opening movable to open position under the influence of gravity, a pivoted member operatively interposed between the door and car body for supporting the door in closed position, and means for cooperating with a removable lever adapted to force the door to closed position, said means involving a member carried by the door forming a seat for said lever and a member carried by the car body forming a pivoted support for the hook and affording a fulcrum for said lever, said members being disposed so as to permit the lever to extend upwardly above the fulcrum point and to operate in a plane substantially parallel to the plane of operation of the pivoted door supporting member.
100

In testimony whereof I affix my signature.
WILLIAM E. WINE.
